UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 19,026, dated April 9, 1889.

Application filed March 7, 1889. Serial No. 302,333. Term of patent 3½ years.

To all whom it may concern:

Be it known that I, HENRY HUNT, a citizen of the United States, residing in Greenville, Hudson county, State of New Jersey, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design contains several groups of diamond-shaped figures, the diamond-shaped fig-

ures being composed of different forms of damask-work and having similar ornamental margins or borders. An irregular stem-work 20 connects these groups together and has branching from it several smaller ornamental figures. Several ornamental figures are also arranged about and branching from the groups of diamond-shaped figures. 25

What I claim as new, and desire to secure by Letters Patent, is—

The design for carpets, consisting of the design substantially as shown.

HENRY HUNT.
